DESIGN FOR A KEEPER PLACER

Alva L. Swearingen and Ralph T. Painton,
Kansas City, Kans.

Application October 10, 1940, Serial No. 95,746

Term of patent 14 years

To all whom it may concern:

Be it known that we, Alva L. Swearingen and Ralph T. Painton, citizens of the United States, both residing at Kansas City, in the county of Wyandotte and State of Kansas, have invented a new, original, and ornamental Design for a Keeper Placer, of which the following is a specification, reference being had to the accompanying drawing, forming a part thereof.

Fig. 1 is a perspective view of the keeper placer, showing our design.

Fig. 2 is an edge elevational view thereof; and Fig. 3 is an end elevational view thereof.

We claim:

The ornamental design for a keeper placer, as shown.

ALVA L. SWEARINGEN.
RALPH T. PAINTON.
